Ind., a corporation of Indiana

Application April 2, 1938, Serial No. 199,635

16 Claims.

(Cl. 261—69)

This invention relates to charge forming devices, and more particularly to carburetors or charge forming devices of the pressure feed type.

An object of the invention is to simplify and improve devices of the type indicated.

Further objects of the invention will be apparent from the following description, taken in connection with the appended drawings in which:

Figure 1 is a diagrammatic sectional view of a device embodying the invention;

Figure 2 is a fragmentary sectional view of a modified form of stem guide and seal, which may be substituted for the corresponding parts shown in Figure 1;

Figure 3 is a diagrammatic sectional view of a modified form of the invention; and

Figure 4 is a fragmentary sectional view of a modified stem guide, which may be substituted in the embodiment shown in Figure 3.

In the embodiments illustrated in the drawings, the arrangement is that used with radial aircraft engines, though it will be apparent that the invention is not limited to such use.

Referring more specifically to the drawings, the device disclosed in Figure 1 comprises a charge forming device including an induction passage 10, communicating with a supercharger 12 of any suitable type, which in turn leads to an intake manifold 14 and thence to the inlet port, not shown, of an internal combustion engine. The passage 10 is controlled by a throttle 16 which is operated by rod 18 extending from the pilot's cockpit. Anterior to the throttle 16 is an air scoop 20 of any suitable construction, which leads to a primary venturi 22, concentrically located in a secondary venturi 24 of any suitable contour. The primary venturi 22 is provided with an annular chamber 26 opening into the venturi in the vicinity of the Venturi throat, so that said chamber and connected passages will be subjected to the depression existing at the Venturi throat. The secondary venturi is also provided with an annular chamber 28 which communicates with the air scoop 20 through a plurality of tubes 30, so that the pressure existing in the air scoop will be transmitted to chamber 28 and its connected passages, hereinafter described.

Posterior to the throttle is a fuel discharge nozzle 32, controlled by valve member 34, which is fixed to a flexible diaphragm 36 and urged towards closed position by a compression spring 38. A fuel passage 40 supplies fuel under pressure to the chamber 42 of the nozzle, whence it is sprayed into the induction passage 10.

The fuel control mechanism of the device comprises an annular fuel chamber 44, a sleeve valve 46, and radial ports 48 in said valve so arranged that axial movement of the valve regulates the available area for fuel flow therethrough. An adjustable stop 49 limits the downward movement of the valve 46. Chamber 44 is supplied with fuel from a fuel pump 50 which may be of any suitable commercial design, the one shown being of the radial vane type, having a fuel inlet 52 and a bypass passage 54 controlled by a pressure responsive relief valve 56 so as to supply fuel at substantially constant pressure to an outlet passage 58 which leads to the annular fuel chamber 44.

10 The mechanism for controlling valve member 46 comprises a casing 60 divided into chambers 62, 64, 66, and 68 by relatively large flexible actuating diaphragms 70 and 72, and by a small sealing diaphragm 74 secured to a rigid partition 20 76, a portion of said partition, indicated at 78, serving as a bearing for the control rod assembly, yet to be described.

25 The diaphragms used in the control unit are preferably formed of material such as silk fabric impregnated with Neoprene or other artificial rubber compound. Such diaphragms have very little inherent resiliency. The area of the sealing diaphragm 74 is small relative to that of actuating diaphragms 70 and 72, and the effect of 30 the pressures on it may be compensated for by modifying the size of metering orifice 83. Several ports 80 connect chamber 66 with chamber 62 to prevent air, which might otherwise be 35 trapped in chamber 62, from acting as an air cushion which would interfere with the freedom of motion of the rod assembly.

40 The control rod 84 is secured to the actuating diaphragms 70 and 72 by plates 86 and 88, which are held in place by fixed sleeves or hubs 87 and 88. The rod 84 is secured to sealing diaphragm 74 by hubs 87 and 88; the entire assembly being clamped securely by tightening a cap 90 on the end of rod 84. Cap 90 is provided with a ball end 45 having a free sliding fit in a socket 91 formed in the casing 60 and serving as a bearing for the rod assembly. This bearing, together with the bearing 78, serves to support and align the control rod assembly in the casing 60.

50 At its lower end rod 84 is connected through two ball type universal joints 95 to sleeve valve 46, thereby permitting a considerable amount of misalignment to be present between the control rod assembly and said sleeve valve without affecting the freedom of motion of said assembly.

Chambers 62 and 68 are interconnected by a fuel passage 92 which is provided with a calibrated orifice 93. Chamber 66 and its interconnected chamber 82 communicate by passage 94 with the annular chamber 28 in the venturi 24 and are therefore subjected to the pressure existing in the air scoop 20. Chamber 64 is connected by passage 95 with the annular chamber 26 in the primary venturi 22 and is therefore subjected to the depression existing at the throat of said primary venturi, which varies as a function of the rate of air flow through the induction passage 10.

When the engine is in operation, pump 50 supplies fuel at substantially constant pressure to the fuel chamber 44, whence it flows through ports 48 into the unmetered fuel chamber 68, thence through passage 92 and restriction 93 to the metered fuel chamber 62, and thence through passage 40 to nozzle chamber 42, where it exerts pressure on diaphragm 36, opening the valve 34 and being discharged into the induction passage posterior to the throttle. Hence the pressure in chamber 68 is greater than that in chamber 62 by the amount of the pressure drop across the metering orifice 93. The resultant of the forces exerted on rod 84 by the fuel pressures will be in a direction to close the valve 46, and since the flow through an orifice is proportional to the square root of the pressure drop across the orifice, the resultant force exerted on rod 84 by the fuel pressures will be proportional to the square of the rate of fuel flow.

Also when the engine is operating, the absolute pressure in chamber 66 will always be greater than that in chamber 64 by the amount of pressure differential between Venturi throat and air scoop. The resultant force on the rod 84 of these pressures will therefore be in a direction to open the valve 46, since the differential in pressure between the Venturi throat and Venturi entrance varies as the square of the rate of flow of fluid through it, the resultant force exerted by the air pressures on rod 84 will be proportional to the square of the air flow. Since, for any given set of operating conditions, the rod 84 and attached valve 46 will move to such a position that the above two resultant forces will be in equilibrium, it is apparent that the rate of fuel flow will be adjusted by valve 46 to be directly proportional to the rate of air flow, thereby providing a constant mixture ratio throughout the range of air-flows utilized, unless varied by other means.

It is to be noted that in the instant invention four adjacent chambers are provided, the center two of which are subjected to pressures of one fluid having a differential therebetween, and the end two are subjected to pressures of the other fluid having a differential therebetween. The particular arrangement of the pressures relative to the chambers and the relative areas of the diaphragms should be such that the effective force resulting from the air differential pressure will tend to move the fuel valve in a direction to increase the fuel flow and the effective force resulting from the fuel differential pressure will be in the opposite direction tending to move the fuel valve in a direction to decrease the fuel flow, it being apparent that if both effective forces were in the same direction proper proportioning of the air and fuel would not be obtained.

In Figure 1 the large diaphragms 70 and 72 have a primary function of actuating the control

rod and have been referred to herein as actuating diaphragms; whereas the small diaphragm has a primary function of sealing and has been referred to as a sealing diaphragm. It is pointed out, however, that the center diaphragm may be larger than the one shown, provided a differential is maintained between the area of the middle and the outer diaphragms so that the differential in the pressures in the center two chambers will create a net force tending to actuate the fuel valve, it being apparent that if the three diaphragms of Figure 1 were the same size these pressures would have no effect on the fuel valve and fuel to air proportioning would not be obtained.

A modified form of the central section of the control unit is shown in Figure 2, and in many respects is similar to the embodiment shown in Figure 1. For this reason, like parts are given like symbols with the addition of 100.

It has been found in practice that an air-tight seal between the air chambers 164 and 166 is not essential, and that the leakage resulting from a small communicating orifice of constant cross-section between said chambers, merely decreases the mixture ratio to some smaller but constant value and may be compensated for by changing the size of the metering orifice. To this end, the rigid partition 176, in the embodiment shown in Figure 2, has been so constructed that the part of said partition indicated at 178, is accurately machined to form a bearing for the hub 188, whereas that portion of said partition indicated at 179 is accurately machined to provide a fixed clearance around hub 188. By using ports 180 to bypass air around the bearing 178, the quantity of leakage becomes independent of the bearing fit and is dependent only upon the amount of clearance provided at 179. Since whatever wear takes place will occur at the bearing 178 and not at 179, the area for leakage is of a fixed and known amount and can therefore be accurately compensated for as hereinbefore explained.

The modification shown in Figure 3 is generally similar to the embodiment shown in Figure 1 and hence corresponding parts are given like symbols with the addition of 300.

Fuel is received from the fuel pump, not shown, through the passage 358, whence it flows into the annular fuel chamber 344, through valve ports 348, into the unmetered fuel chamber 368, thence through passage 392 and metering orifice 393 into the metered fuel chamber 362, and thence through passage 340 to the discharge nozzle, not shown. Several ports 380 are located in the valve 346 to provide communication between chamber 382 and the unmetered fuel chamber 368, thereby insuring that chamber 382 and the surface of the diaphragm 374 adjacent said chamber will be subjected to unmetered-fuel pressure.

Chamber 364 communicates through passageway 395 with the annular chamber 26 in the primary venturi 22 (Figure 1), and is therefore subjected to the pressure existing at the throat of the primary venturi. Chamber 366 communicates through passageway 394 with the annular chamber 28 in the secondary venturi 24 (Figure 1), and is therefore subjected to the pressure existing in the air scoop.

As hereinbefore explained with reference to Figure 1, the differential in pressure between air scoop and primary venturi produces a net resultant force on control rod 384 and attached valve 346 which is proportional to the square of the rate of air flow and acts in an upward direction

tending to open valve ports 348. The differential in pressure between the unmetered fuel in chamber 368 and the metered fuel in chamber 362, caused by the drop in pressure across the metering orifice 393, results in a net force acting on control rod assembly 384 which is proportional to the square of the rate of fuel flow and acts in a downward direction tending to close valve ports 348.

For any given set of operating conditions, the control rod assembly and valve 346 will adjust themselves to a position wherein the above two resultant forces will be in equilibrium, and hence the quantity of fuel flowing will be maintained in constant proportion to the quantity of air flow unless altered by some extraneous force such, for example, as the force exerted by idle spring 397 which is shown in Figure 3 as a compression spring surrounding a fixed stop 398 and having its upper end provided with a thimble 399 which is normally spaced from a nut 400 which is attached to the lower end of the control rod 384. At valve port openings greater than for idle operation, the rod 384 is entirely free of spring 397; however, when idle operation is approached, the thimble 399 contacts the nut 400 and exerts thereon an upward force tending to keep valve ports 348 in open position. This extraneous spring force is equalized by increased fuel flow, producing an enriched mixture for idle and near idle operation.

A modified form of the central section of the control unit of Figure 3 is shown in Figure 4, in which the central sealing diaphragm has been eliminated. By making the valve 446 a very close, lapped, fit in the partition 476 the fuel leakage from chamber 444 past the sleeve valve 446 into the chamber 464 can be reduced to a small amount. Since the pressure in fuel chamber 442 is maintained substantially constant by the fuel pump and the pressure in metered fuel chamber 464 is also maintained substantially constant by the discharge nozzle, the leakage past the valve will be a very nearly constant amount throughout the operating range. The quantity of leakage is a negligible percentage of the total fuel flowing at all conditions except at, or near, idle operation. At such conditions of operation the amount of leakage, though small, is a perceptible percentage of the total fuel flowing and hence will noticeably enrich the mixture. However, at idle operation an even greater enrichment than that resulting from leakage is required and is obtained by the use of an idle spring as hereinbefore explained.

In the description of the several embodiments of the invention, the terms "upward" and "downward" have been used for convenience, but it will be understood that the control mechanism may be inverted relative to the carburetor, or the control unit and carburetor may both be inverted relative to the engine, or the engine and all its accessories may be inverted (as in acrobatic flight) without greatly affecting the operation as above described. In other words, the device is substantially unaffected by forces of gravity and acceleration, and is therefore especially suitable for inverted or acrobatic flight.

Although the invention has been described with particular reference to specific embodiments thereof, it is not limited to such use, and may be embodied in other forms within the scope of the appended claims.

I claim:

1. In a charge forming device, an induction

passage, a throttle therein, a venturi in the passage anterior to the throttle, a fuel conduit leading from a source of fuel under pressure to the induction passage posterior to the throttle, a pressure responsive valve controlling the conduit adjacent its outlet in the passage, a metering orifice in the fuel conduit, a valve for controlling the flow of fuel through said conduit, and control means for said valve comprising a casing, a rigid partition in said casing, two actuating diaphragms in said casing on opposite sides of said partition, said partition and diaphragms dividing the casing into four chambers, a control rod passing through an aperture in the partition and connected to the diaphragms and to the fuel control valve, pressure transmitting means connecting the two chambers separated by the partition respectively to the venturi and to the induction passage anterior to the throttle and being so arranged that an increase in the differential in the pressures in the said two chambers tends to result in movement of the valve in a direction to increase the fuel flow to the induction passage, and means communicating the other two chambers respectively with the fuel conduit on opposite sides of the metering orifice and being so arranged that an increase in the differential in the pressures in the said other two chambers tends to result in movement of the valve in a direction to decrease the fuel flow to the induction passage.

2. In a charge forming device for an internal combustion engine, an air passage, a throttle therein, a fuel conduit leading from a source of fuel under pressure to the air passage posterior to the throttle, a pressure responsive valve controlling the conduit adjacent its outlet in the air passage, means in the air passage anterior to the throttle for creating a pair of pressures the difference between which varies in accordance with the rate of air flow therethrough, means in the fuel conduit for creating a pair of pressures the difference between which varies in accordance with the rate of fuel flow therethrough, and a control unit for controlling the flow of fuel to the air passage comprising a casing, a partition in the casing, a pair of actuating diaphragms in said casing on opposite sides of said partition, said diaphragms and the partition and the casing forming four chambers, an aperture in the partition, control rod means passing through the aperture and connected to said diaphragms to be actuated thereby, a fluid control valve connected to the control rod means and in coaxial alignment with the control rod means and the diaphragms for varying the flow of fuel through the fuel conduit, means for subjecting the chambers on opposite sides of the partition and adjacent thereto respectively to the pressures constituting one of said pairs of pressures, and means for subjecting the other two of said four chambers respectively to the pressures constituting the other of said pairs of pressures, said subjecting means being so arranged that increases in the first and second named differences in pressures tend to result respectively in movement of the fuel valve in directions to increase and decrease the fuel flow to the air passage.

3. The invention defined in claim 2 comprising in addition a small sealing diaphragm connected to the partition and to the control rod means to prevent flow through said aperture.

4. In a charge forming device for an internal combustion engine, an air passage, a throttle in the passage for variably controlling the air sup-

plied to the engine, a fuel pump, a fuel conduit connecting the pump to the air passage, means in the air passage anterior to the throttle for establishing a pair of pressures the differential of which varies in accordance with variations in the air flow therethrough, means in the fuel conduit for establishing a pair of pressures the differential of which varies in accordance with variations in the fuel flow therethrough, and means for controlling the fuel flow to the air passage comprising a casing, a rigid partition separating the casing into two end compartments, diaphragms in the end compartments dividing the casing into four pressure chambers two of which are separated by said partition, means for subjecting the said two chambers respectively to the pressures constituting one of said pairs of pressures, means for subjecting the other two chambers respectively to the pressures constituting the other of said pairs of pressures, control rod means extending through the partition and connected to said diaphragms to be actuated thereby, and means including a valve connected to the control rod means for varying the flow of fuel through the fuel conduit, said diaphragms, control rod means, and valve being coaxially aligned, and said subjecting means being so arranged that increases in the first and second named differential of pressures respectively tend to move the valve in opposite directions.

5. In a charge forming device for an internal combustion engine, an air passage, a manually operable throttle in the passage for variably controlling the supply of air to the engine, a fuel nozzle discharging into the passage, a source of liquid fuel under pressure, a conduit connecting said source and the nozzle, metering elements in the air passage anterior to the throttle and in the fuel conduit respectively creating air and fuel differential pressures variable in response to variations in the air and fuel flow therethrough, and means for controlling the fuel flow to the nozzle including a control unit casing, means including a pair of actuating diaphragms and an apertured partition therebetween dividing the casing into four compartments, a control rod extending through the aperture and connected to said diaphragms, a relatively small sealing diaphragm connected to the control rod and to the partition, a valve for controlling the flow of fuel to the nozzle connected to said rod to be actuated thereby, said valve being in coaxial alignment with the control rod and with the diaphragms, means for subjecting the outer faces of said actuating diaphragms to one of said differential pressures tending to urge the valve in one direction and means for subjecting the inner faces of said actuating diaphragms to the other of said differential pressures tending to urge the valve in the opposite direction.

6. In a charge forming device for an internal combustion engine, an air conduit, a throttle in the conduit, a fuel conduit for receiving fuel under pressure from a source and supplying it to the engine, a fuel control valve in the fuel conduit, means in the air conduit establishing a pair of air pressures the difference of which varies with variations in air flow through the air conduit, means in the fuel conduit for establishing a pair of fuel pressures the difference of which varies with variations in fuel flow through the fuel conduit, a casing, a pair of distortable pressure responsive members and a diaphragm therebetween in said casing dividing the casing into and forming parallel movable walls of four cham-

bers, said members and diaphragm being operatively connected to the fuel control valve, and means for exposing the center two chambers to one of said pairs of pressures and the end two chambers to the other of said pairs of pressures, the differential in the pair of air pressures tending to move the fuel valve in a direction to increase the fuel flow to the engine and the differential in the pair of fuel pressures tending to move the valve in a direction to decrease the fuel flow to the engine.

7. In a charge forming device for an internal combustion engine, an air passage for supplying air to the engine, a throttle in the passage, a liquid fuel conduit for supplying fuel to the engine, means in the air passage anterior to the throttle for creating a pair of air pressures the difference of which varies in accordance with variations in the air flow therethrough, means in the fuel conduit for creating a pair of fuel pressures the difference of which varies in accordance with variations in the fuel flow therethrough, and a control unit comprising a casing, means including a pair of actuating diaphragms and a rigid partition therebetween for forming four pressure chambers in said casing, an aperture in the partition, a control member including a fuel valve for controlling the fuel flow through said conduit extending through the aperture and connected to said actuating diaphragms, means for subjecting the chambers adjacent the partition respectively to the said pair of air pressures, and means for subjecting the end chambers respectively to said pair of fuel pressures, said diaphragms, partition and subjecting means being so arranged that increases in the differential in air pressures and in the differential in fuel pressures tend to result respectively in movement of the valve in directions to increase and decrease the fuel flow to the engine.

8. The invention defined in claim 7 wherein the aperture comprises a bearing portion for the control member, a second portion closely surrounding the control member but spaced therefrom to form a calibrated area for leakage, and a by-pass around the said bearing portion whereby the leakage between the said adjacent chambers will be determined by the calibrated area.

9. In a charge forming device for an internal combustion engine, an air passage, a fuel conduit, a control unit comprising adjacent chambers subjected to variable air pressures developed in the operation of the engine, a rigid partition between said chambers, an aperture in the partition, diaphragms forming movable walls of each of said chambers, a movable control member extending through said aperture and connected to said movable walls to be actuated thereby, and a valve connected to the control member for varying the quantity of fuel flowing through said conduit, said aperture having a bearing portion for supporting the control member and a second portion closely surrounding said control member but spaced therefrom to form a calibrated area for leakage, and means for passing air past the bearing portion whereby the leakage between the adjacent chambers will be determined by the calibrated area.

10. In a charge forming device for an internal combustion engine, a control unit comprising a casing, a pair of actuating diaphragms and a rigid partition therebetween forming four adjacent chambers in said casing, an aperture in said partition, a movable control member extending through said aperture and connected to said ac-

tuating diaphragms, and a valve attached to said control member and cooperating with the aperture in said partition, a fuel conduit for supplying fuel to the engine including a portion within said partition controlled by said valve, a metering restriction in the fuel conduit, means communicating the center two chambers respectively with the conduit anterior and posterior to the restriction, an air passage for supplying air to the engine, means in said air passage for creating a pair of air pressures the differential of which varies in accordance with variations in the flow through the air passage, and means communicating said air pressures respectively to the two end chambers.

11. The invention defined in claim 10 comprising in addition a sealing diaphragm connected to said partition and to the control member.

12. In a charge forming device for an internal combustion engine, a control unit having four adjacent chambers, actuating diaphragms separating the first and second chambers and the third and fourth chambers respectively, a partition separating the second and third chambers, an aperture in the partition, a fuel passage within the partition communicating with said aperture and transmitting fuel to be supplied to the engine, a movable control element extending through the aperture and connected to said diaphragms, a valve connected to said element and cooperating with said partition to control the fuel flow through said passage, means for subjecting the second and third chambers to fuel pressures the differential of which varies in accordance with the fuel flow to the engine, and means for subjecting the first and fourth chambers to air pressures the differential of which varies in accordance with the air flow to the engine.

13. The invention defined in claim 12 comprising in addition a relatively small sealing diaphragm connected to the control element and to the partition to prevent leakage through said aperture between the second and third chambers.

14. In a charge forming device for an internal combustion engine, an air passage for supplying air to the cylinders of the engine, a throttle therein, means in the air passage anterior to the throttle for creating a pair of pressures the differential of which varies in response to variations in air flow therethrough, a liquid fuel conduit leading from a source of fuel under pressure to the air supply passage posterior to the throttle, a pressure responsive valve controlling the conduit adjacent its outlet in the passage, means in the fuel conduit for creating a pair of pressures the differential of which varies in response to variations in fuel flow therethrough, a valve for controlling the flow of fuel through said conduit, and control means for said valve comprising a casing, a rigid partition in said casing, two actuating diaphragms in said casing on opposite sides of said partition, said partition and diaphragms dividing the casing into four chambers, a control rod passing through an aperture in the partition and connected to the diaphragms and to the fuel flow control valve, said rod, valve and diaphragms

being in coaxial alignment means for transmitting one of said pairs of pressures to the chambers separated by the partition, and means for transmitting the other of said pairs of pressures to the other two chambers respectively, said transmitting means, chambers, diaphragms and control valve being so arranged that increase in the differential of one of the pairs of pressures tends to increase the fuel flow to the air passage, and increase in the differential of the other pair of pressures tends to decrease the fuel flow to the air passage.

15. In a charge forming device for an internal combustion engine, an air passage for supplying air to the cylinders of the engine, a throttle in said passage for variably controlling the air supply, means in the air passage anterior to the throttle for creating a pair of air pressures the differential of which varies in response to variations in flow therethrough, a fuel conduit for supplying fuel to the engine, a metering element in the conduit for creating a pair of fuel pressures the differential of which varies in response to variations in flow therethrough, a control unit 20 casing, a rigid partition in the casing, two actuating diaphragms in said casing on opposite sides of said partition, said partition and diaphragms dividing the casing into four chambers, means for subjecting the chambers separated by the 25 partition respectively to the said pair of fuel pressures, means for subjecting the other chambers respectively to the said pair of air pressures, a central aperture in the partition in coaxial alignment with the diaphragms, and means for varying the fuel supply to the engine in accordance with variations in the air supply comprising a fluid passage in said partition communicating with said aperture, and a valve connected to said diaphragms and cooperating with said aperture to variably control said fluid passage.

16. In a carburetor of the type described, a hollow body member for attachment to an engine intake, a fuel-air mixing chamber in the body member and an air conduit through the body member delivering to said chamber, a fuel conduit including a discharge orifice delivering to said chamber, means for supplying fuel to said fuel conduit under pressure, means for establishing differential pressures in the air conduit and in the fuel conduit, a pair of distortable pressure-responsive means in fixed relation to the body member coupled to each other in spaced relation and each adapted to deflect under influence of fluid pressure, the nearest proximate sides of said means being exposed to differential pressure in one of said conduits and the farthest remote sides of said means being exposed to differential pressure in the other conduit, valve means in the fuel conduit in operative driven connection with said coupled means and arranged to be urged thereby 45 toward open position on increase in differential pressure in the air conduit and urged toward closed position by increase in differential pressure in the fuel conduit, and throttle means in the body member adjacent said mixing chamber.

EDWARD J. PARTINGTON.
